United States Patent Office.

PHENDEUS H. LEWIS, OF BOSTON, MASSACHUSETTS.

Letters Patent No. 85,943, dated January 19, 1869.

IMPROVED WASHING-MACHINE.

The Schedule referred to in these Letters Patent and making part of the same.

To all whom it may concern :

Be it known that I, PHENDEUS H. LEWIS, of Boston, in the county of Suffolk, and State of Massachusetts, have invented a new and useful Improvement in Washing-Machines; and I do hereby declare that the following is a full, clear, and exact description of the construction and operation of the same, reference being had to the accompanying drawing, forming a part of this specification.

This improvement consists in a new arrangement and adjustment of parts in a washing-machine, by which it is made self-adjusting, and more serviceable and easily cleaned.

In the drawings—

Figure 1 is a longitudinal section of the machine.

A is the drum. It is made of heads, into which are framed alternately slats *a*, of a trapezoid section, the short side out, and in the intervals of these slats, other slats, *b*, of an angular section, filling the intervals, and presenting their angle outward.

This is hung in the centre of a loose-jointed frame, B, pivoted to the wash-tub C, at its end, and extending around the same.

A tongue, *c*, extends downward from this frame, and is pierced with holes to receive a spring-lever, *d*, below to the tub, at one end, having a fulcrum, *h*, in the centre of the bottom of the tub.

The wash-tub C is a square or rectangular box, with legs at its corners.

At its corners in the interior are ledges *e*, and within it is placed the concave wash-board D.

This is a wooden frame fastened to two slats *f*, which

rest on the ledges *e*, and have a slight spring or yielding motion.

Buttons *g* are put on the ends of these slats—to raise the frame in the tub, and obtain a greater or less pressure upon the material to be washed.

Between the sides of the frame of the wash-board are placed rollers *h*, freely revolving.

The operation of this machine is as follows:

The tub is filled with water, wash-board D is placed in position, and the buttons on slats *f* arranged so as to suit the thickness of clothing to be washed. The frame B is brought over so that drum A rests in the centre of the wash-board, and the spring-lever *d* brought up against the fulcrum *h*, and fastened through the tongue *c*. The clothes to be washed are then fed in from one or the other side, and the drum receives a rotary motion to bring them between the drum-slats and the wash-board, and a reciprocating rotary motion to give them the necessary scrubbing. These two motions accommodate themselves to the work by means of the spring-slats of the wash-board and the arrangement of the frame in which the drum is hung.

What I claim as my invention, and desire to secure by Letters Patent, is—

The arrangement of drum A, frame B C, spring-lever *d*, and fulcrum *h*, with reference to tub C, when the wash-board D is arranged within it by means of spring-levers *f* and ledges *e*, all substantially as described.
